WILLIAM S. MURRAY, OF UTICA, NEW YORK, ASSIGNOR TO ONEIDA COMMUNITY,
LIMITED, OF ONEIDA, NEW YORK, A CORPORATION OF NEW YORK

METHOD OF AND APPARATUS FOR PRESSING MATERIALS INTO MOLDS

Application filed May 18, 1932. Serial No. 364,129.

This invention relates to an improved method of and apparatus for pressing material into molds.

It has been common in the art heretofore to press suitable ductile material, for example, metal, into molds by the use of fluid or liquid under high pressure, which acted directly against one face of the material to be pressed and thereby forced such material into contact with the inner face of the mold.

Where the object to be formed was a hollow body, the fluid pressure applied to the interior of such body served to expand it wherever permitted by the mold, with the result that the expanded portions were thinner than those portions of the hollow body which were not expanded. The resultant article so made was not of uniform or substantially uniform thickness throughout, but was of appreciably different thicknesses. As a result, the blank which is to be expanded must have a wall thickness much greater than the wall thickness of the finished article at the expanded portions, thus leaving the unexpanded portions unnecessarily thick so that the completed article is unnecessarily heavy and more expensive on account of the cost of the additional metal.

Furthermore, because the blank is thicker than necessary for the expanded portions of the finished article, much heavier pressures are required at starting to expand the metal.

To overcome the foregoing disadvantages, a method has been proposed which consists in gradually expanding the metal of the blank and during the expanding process maintaining a flow of the metal to the expanded portions so as to provide a sufficient thickness at the places which would otherwise be thinned by the expansion. In carrying out this method, the blank is subjected not only to an internal pressure, capable of expanding it, but also to a separately controlled upsetting force,—that is, to a force which tends to compress the blank and “upset” it or thicken it at the part being expanded, the upsetting force being such as to cause a proper flow of the metal into the expanding portion of the blank. The upsetting force is conveniently

provided by a plunger which acts on the end of the blank.

Attempts to practice this method have proved unsuccessful, in the past, for the reason that the blank end receiving the upsetting pressure deforms, collapses or buckles laterally and does not transmit such pressure to the expanding portions of the blank nor provide the desired flow of metal thereto.

It is the object of the present invention to eliminate this defect.

According to the present invention, the blank, which is usually a hollow body, is supported against lateral crimping, collapse, or buckling during the application of the upsetting force. Such support is advantageously provided over all of the unexpanded portions of the blank receiving the upsetting pressure or compression. The unexpanded portion of the blank receiving the upsetting pressure, being thus unable to collapse laterally, must necessarily collapse in the direction of the expanding portion of the blank and consequently metal from the unexpanded portion is caused to flow into the expanding portion.

While apparatus of different types may be employed for carrying out the new method, the present invention includes apparatus particularly advantageous for the purpose.

In the drawings:

Figures 1-3 inclusive, are detail sectional views illustrating the manner of producing an automobile housing in accordance with the invention, Figure 2 being a sectional view on line 2—2 of Figure 1, and Figure 3 similar to Figure 2 and showing a further stage in the process;

Figure 4 is a diagrammatic view illustrating a type of apparatus for practicing the invention;

Figures 5-8 inclusive, are detailed views of the same.

The invention is exemplified in the manufacture of a seamless or weldless housing for automobile axles. Heretofore, such housings have been made of two or more parts and then welded together. In accordance with the present invention, a stronger and more reliable housing is made more rapidly and economically by expanding a tube of

suitable material in a matrix having the proper interior configuration, the expansion being done by a fluid or hydraulic pressure applied internally, while at the same time an upsetting pressure is applied to the ends of the tubular blank to insure a travel or flow of metal into the expanding portions of the blank and the unexpanded portions of the blank supported against lateral collapse or buckling to insure flow of metal from the unexpanding portion of the blank to the expanding portion.

In Figures 6 and 7 is illustrated a practical form of die-holding device which has the advantage that the matrix may be quickly opened for the insertion and removal of a blank and quickly closed. In this, the die-holder has an open base formed of the integral parts 115, 116 and 116¹ so as to leave an opening through the base to permit the insertion of cross-bars 118, each of which projects, at both ends, beyond the base, the projecting ends having screw-threaded holes into which are screwed stud bolts 119 having nuts 119¹. Across the top of the die-holder are placed two upper cross-bars 121, each forked at one end 121² to engage beneath the nut of one stud bolt and laterally slotted at the other end 121¹ to engage beneath the nut of the other stud bolt of its respective pair of stud bolts. Each upper cross-bar is provided with a pressure screw 124 having a handwheel 124¹.

By screwing this hand-wheel down, the two parts 113 and 114 of the die-holder, which carry the matrix halves 111 and 112, are forced into close contact with each other. When it is desired to open the die-holder and matrix, it is only necessary to turn the hand-wheel, and swing the upper cross-bars 121 angularly to release their laterally slotted ends, 121¹, and then draw their other ends, 121², from beneath the corresponding stud bolt nuts. The matrix parts are attached to the respective parts of the die-holder by screws 47 or other fasteners.

Figures 4, 5 and 8 show a form of apparatus for applying an internal expanding pressure and an upsetting pressure to the blank, with means for supporting against lateral collapse the unexpanded portions of the blank. In this exemplification, the expanding pressure is supplied by hydraulic means and the upsetting pressure by mechanical means.

In this case each end of the blank is acted upon by a ram or plunger 88, 88¹, respectively, carrying the mandrels 91, 91¹, respectively, each plunger being mounted in the end of a longitudinally movable but non-rotatable screw, these screws being indicated at 86, 86¹. Each screw is movable longitudinally through openings in two pedestals, 92, 93, 92¹, 93¹, each of the pedestals 92, 92¹, being provided with a feather, one of which

is indicated at 95, Fig. 5. On each screw 86, 86¹, is mounted a rotatable nut 96, 96¹ to each of which is fixed a gear wheel 97, 97¹. In the usual practice, the gear wheel is fixed to its nut by a spline which enters cooperating grooves, one in the hub and the other in the gear-wheel. One of these splines is indicated at 97², Fig. 5.

The inner end of each nut is flanged to bear against the flange of a liner for its corresponding pedestal 93, 93¹, one of these liners for the pedestal 93 being indicated at 93², Fig. 5. The outer end of each nut is arranged to bear against a ball-bearing device which is located between the said inner end of the nut and the outer pedestal 92, 92¹. One such ball-bearing device is shown in section at Z in Fig. 5. It comprises two bearing rings or washers and an intermediate ball-carrying ring or separator provided with equally spaced openings in which the balls are located. One of the screws, its plunger and mandrel are hollow or tubular to conduct liquid under pressure to the interior of the blank. In the construction illustrated, the screw 86 is provided with a central passage 84 and its plunger 88 and mandrel 91 are shown as made integral with a central passage 90. The outer end of the screw 86 is connected by a union 87 with a pipe 85 longitudinally movable through a pedestal head 84¹ carried on a pedestal 84², a suitable stuffing box being provided for the pipe 85, as will be clear from Fig. 5. The outer end of the pipe 85 slides telescopically in the pipe 83. 100

The means for supplying liquid under pressure to the pipe 83 and for exhausting it from said pipe may take any desired form. In this exemplification, the pipe 83 is supplied with high pressure liquid through a pipe 17 which may receive liquid under pressure from pipe 14, the supply from pipe 14 being controlled by a valve 14¹. Also the pipe 17 may be supplied with liquid under a regulable and still higher pressure from an intensifier 22 provided with suitable pipe connections and valves which may be of any preferred construction. Inasmuch as such intensifier forms no part of this invention, it is not illustrated in detail. The supply to pipe 14 is from pump B. The exhaust from pipe 83 is through a pipe 29 equipped with a valve 29¹. Pipe 14 may advantageously be provided with a safety valve 18, and the system generally modified and refined in detail. 110

The gear wheels 97 and 97¹ are driven simultaneously by the respective pinions 98, 98¹, fixed on a pinion shaft 99 journaled in suitable bearings carried by the pedestals 93, 93¹, respectively, as will be clear from Fig. 4. 125 To the pinion shaft 99 is fixed a gear wheel 101 which meshes with a driving pinion 102 fixed on a shaft 104 mounted in suitable bearings 125, 125¹.

The transmission shaft 104 is driven from 130

a power shaft 106, through a two-speed transmission gearing of the usual shifting gear type indicated generally by the reference letter 105 in Fig. 4.

5 The power shaft which is mounted in a bearing 106¹ has fixed to it a worm-wheel 107, engaged by a worm 110 fixed on the motor shaft 109 of a suitable electric motor indicated at 108. This motor is of the reversible type, so that the nuts 96, 96¹, may be rotated 10 in either direction, to permit the screws to be moved longitudinally outward as well as inward whenever required.

15 The screws carry the plungers 88, 88¹ with their mandrels 91, 91¹. The plungers are adapted to bear against the ends of the blank and the mandrels to fit snugly within said ends. Movement of a plunger inward thus supplies the upsetting pressure to the blank. 20 The mandrels provide the supporting means for preventing the unexpanded portions, in this case, the ends, from collapsing or buckling inwardly. As shown in Figure 8, each mandrel is sufficiently long to extend at all 25 times into the tube end overall the unexpanded end portion of the tube and up to or beyond the point where expansion occurs and thus internally supports the tube while the die or matrix provides an external support. 30 It should be mentioned that the buckling, crimping or lateral collapse herein referred to is the result of several elements, to wit—the thinness of the walls of the blank or tube, which renders them unadaptable for sustaining or transmitting upsetting pressure or compression, and the frictional resistance offered to flow of the metal by the contacting surfaces of the die. By supporting the tube internally as well as externally throughout 35 the entire range of the unexpanded portions receiving the upsetting or compression, such deformation is eliminated.

40 The manner of practicing the invention in the formation of the seamless housing will be clear from Figures 1, 2 and 3. Figure 1 shows the starting blank 50 which is usually a seamless drawn tube of low carbon steel or iron. This tube 50 is inserted in the matrix and the plungers 88, 88¹ are brought quickly 45 into contact with the ends of the blank by setting the shift gear mechanism for high speed rotation of the shaft 104 and then starting the motor 108 to run in the proper direction to drive the screws 86, 86¹ toward each other. The matrix illustrated has an 50 enlarged central part *a* where expansion is to occur and end parts *a*¹ which are reduced and fit the exterior of the tube to prevent its expansion and maintain it unexpanded. The 55 mandrels enter the ends of the tube, and, when the plungers contact with the tube ends, but before the application of pressure thereto, the mandrels are internally supporting the tube over their entire portions between 60 their ends and the points where expansion

occurs. Thus, while the upsetting forces are applied to the ends of the tube, the unexpanded portions of the tube are supported against lateral collapse or buckling. When the plungers 88, 88¹ make or approach to contact with the ends of the blank, the transmission gears are shifted to drive the shaft 104 at a slower speed proportionate with the rate of expansion and force the plungers slowly against the tube ends, and thereupon the 70 liquid pressure is applied to the interior of the blank through pipe 83 by opening valve 14¹. The intensifier 22 may or may not be brought into action to augment the liquid pressure as desired. The internal pressure 80 expands the blank at those places where the inner walls of the matrix are not in contact with the blank. In other words, the blank tends to move into the recesses of the mold. At this time, there would be a tendency of 85 the blank to become thinner at the expanding portions. But at the same time the plungers are forcing the tube ends inwardly, thereby tending to upset or thicken said walls but not actually doing so because of the 90 counteracting effect of the expansion of the blank—that is, metal is flowing into the expanding portion from the ends receiving compression. The internal and upsetting pressures may be regulated as already described. In this way, the blank is forced to fill the interior of the matrix, while, at the same time, the thickness of the wall of the expanded portion is maintained substantially uniform with those of the unexpanded 95 portions because of the flow of metal therefrom. The unexpanded portions are further prevented from collapsing or buckling laterally by the internal supports given thereto by the mandrels. In order to draw the blank 100 to the completed form, it may be necessary to act on it in a series of stages, with different matrices and with annealing between the different stages. For example, Figure 2 represents one stage and Figure 3 a further 110 stage, the latter showing a central portion enlarged to a greater extent than in Figure 2. The process may be carried out in as many stages as desired.

When the blank has been expanded in the 115 matrix and the liquid pressure released, plungers 88, 88¹, may be withdrawn from contact with the blank by reversing motor 108. In order to return the screws and plungers quickly to the starting position, the 120 transmission mechanism may be shifted to the high speed gears.

It will be understood that the plungers 88, 88¹ with their mandrels 91, 91¹ may be replaced by others of different size, according 125 to the nature of the work. For this reason, each plunger may be screw-threaded into the end of the corresponding screw 86, 86¹ and may have an enlargement or flange bearing 130

on the end of the screw, as will be clear from Figure 8.

This application is a continuation in part of my prior application in Serial No. 133,528, filed September 4, 1926.

5 What is claimed is:

1. The method of expanding a hollow blank of ductile material into contact with the interior wall of a matrix, which in part fits the blank and in part is enlarged to allow the blank to expand therein, which comprises subjecting the interior of the blank to a fluid pressure sufficient to expand it radially, while subjecting the metal of the blank to an upsetting flowing pressure whereby metal from the unexpanded portions is supplied to the expanding portions of the blank, and supporting the walls of the unexpanded portions as far as the point of divergence of the expanding portion before and during the subjection of said metal to said upsetting pressure to prevent lateral collapse during application of the upsetting pressure.

2. In combination, means for supplying to the interior of a blank fluid under pressure sufficient to expand the material of the blank, a plunger arranged to act against the end of the blank and to apply upsetting flowing pressure thereto, and a mandrel associated with the plunger and adapted to enter the blank as far as the point of divergence of the expanding portion, said mandrel entering the blank before contact of the plunger to support internally the unexpanded portions of the blank.

35 In testimony whereof, I have hereunto set my hand.

WILLIAM S. MURRAY.
